UNITED STATES PATENT OFFICE.

WILLIAM E. HICE, OF PITTSBURGH, PENNSYLVANIA.

GRINDING APPARATUS.

1,224,169.

Specification of Letters Patent.

Patented May 1, 1917.

Application filed January 29, 1914. Serial No. 815,239.

To all whom it may concern:

Be it known that I, WILLIAM E. HICE, a citizen of the United States, and resident of Pittsburgh, in the county of Allegheny and State of Pennsylvania, have invented a new and useful Improvement in Grinding Apparatus; and I do hereby declare the following to be a full, clear, and exact description thereof.

10 My invention relates to grinding apparatus, and is more particularly adapted for the grinding of lenses, although its application is not in any sense limited to this particular use.

15 The object of my invention is to provide a machine of this character which provides for the grinding of a concave or convex spherical curve to any radius with great accuracy, or a perfect sphere, or two concave and convex spherical curves exactly of the same radius to fit one within the other, the operation being entirely automatic when once the proper adjustments have been made, thereby doing away with the skill heretofore required in the grinding of such curves, and thereby greatly reducing the cost.

20 To these ends my invention comprises the novel features hereinafter set forth and claimed.

25 In the accompanying drawings, Figure 1 is a front view of my improved apparatus partly in section; Fig. 2 is a side view partly in section; Fig. 3 is a cross section on the line 3—3, Fig. 1; Figs. 4, 5 and 6, are 30 details; and Figs. 7 and 8 are views showing the position of the swinging frame in the grinding of a convex and concave lens, respectively.

35 In the drawing the numeral 2 designates a suitable frame provided with the scale 3, the zero point being at about the middle of the scale, for the purpose more fully hereinafter set forth. Screw-shafts 4 are mounted in the frame, the upper ends of said shafts having the beveled pinions 5 which mesh with the beveled pinions 6 on the horizontal shaft 7 mounted at the top of the frame, in suitable bearings 8. A hand-wheel 9 is provided for the shaft 7 and by the turning of this hand-wheel, the simultaneous rotation of the screw-shafts 4 is provided for. Each of the screw-shafts 4 passes through an adjustable slide-block 10 which engages the frame by its guide-way 11. The set-screws 12 are provided for securing said blocks to said frame. The

40 screw-shaft 4 passes down through a threaded opening 13 in the block 10 and when the set-screw 12 is released, the rotation of the screw shaft 4 moves the block 10 up and down on the frame in the manner fully hereinafter set forth. The block 10 is provided with the segmental recess or seat 14.

45 The swinging frame 15 is supported within the frame 2 in the following manner: Trunnion blocks 16 are secured to the uprights 17 of the swinging frame 15 by means of the set-screws 18, and when said set-screws 18 are released the blocks 16 are adjustable up and down on uprights 17 of 50 the swinging-frame 15. The trunnion-blocks 16 carry the knife edged trunnions 19 which enter the seats 14 in the blocks 10. In this manner the swinging frame 15 is supported directly by the blocks 10 and 55 indirectly by the frame 2 to which said blocks are secured. The upper ends of the trunnions 19 do not engage the upper ends of the seats 14 but are spaced slightly therefrom to allow for a certain amount of 60 in-movement of the swinging frame 15 independently of the frame 2.

65 The vertical shaft 20 is mounted in suitable bearings in the swinging frame 15 and said shaft carries the beveled pinion 21 which is engaged by the beveled pinion 22 on the stub-shaft 23 mounted in suitable bearing 24 in the swinging frame 15. The stub-shaft 23 is connected to the flexible shaft section 25 which is interposed between the 70 stub-shaft 23 and the shaft 26. The shaft 26 engages the rotary sleeve 27 a slot 28 in said shaft permitting the longitudinal movement of said shaft in the sleeve 27 while the key 29 connects said shaft with 75 the rotary sleeve 27, so that rotary movement is imparted by said sleeve 27 to the shaft 26 and through the connections described to the vertical shaft 20.

80 The sleeve 27 is mounted in suitable 80 bearings in the uprights 30 and 31, and rotary movement is imparted to said sleeve from the belt 32, which engages the pulley 33 on the sleeve 27.

85 In order to impart a swinging or oscillatory movement to the frame 15, said frame has the bracket extension 34 extending out therefrom, and connected to the outer end of said extension is the link 35 which is connected to the crank-arm 36 on the worm-wheel 37. This worm-wheel 37 is supported 90 by the bracket 38 secured to the upright 95

31. A worm 39 on the sleeve 27 engages the worm-wheel 37, and in this manner an oscillatory movement is imparted to the swinging-frame 15. In order to vary the oscillation of the frame 15, the crank 36 is provided with a series of openings to any one of which the link 35 may be connected to vary the stroke.

Secured rigidly to the lower end of the 10 vertical shaft 20 is the chuck 40. This chuck has the lens supporting member or block 41 which is hinged at 42 to said chuck. The supporting member has the finger 43 which enters a correspondingly shaped seat 44 in 15 the chuck. The set-screw 45 is employed to secure the supporting member 41 at any desired position with reference to the chuck as is indicated in Fig. 6, and in this way the supporting member may be arranged to 20 grind prisms or sphere prisms.

The shaft 20 is movable vertically in its bearing and to provide for the raising and lowering of said shaft the pin 46 engages the rack-portion 47 on the shaft, and a hand-wheel 48 is provided for turning the pinion 46.

In order to hold the supporting block 41 down with sufficient resistance to give the proper grinding effect, I provide the bracket 30 49 on the swinging-frame 15 and said bracket carries the collar 50. The pin 51 has the collar 52 and surrounding said pin and interposed between the collar 50 and the collar 52 is the spring 53, which acts to 35 hold the pin in engagement with the upper end of the shaft 20, while at the same time said shaft can yield slightly if necessary. The bracket 49 can be swung around to one side together with the pin when it is desired 40 to relieve the pressure on the shaft 20 to remove the lens from the supporting block 41.

The lens 54 is cemented or otherwise secured to the supporting block 41, and said lens is in contact with the lap 55 carried on 45 the vertical shaft 56. This shaft 56 is journaled in suitable bearings in the pedestal 57, and said shaft 56 is driven by the belt 58 engaging the pulley 59. By means of the adjusting screw 60 the position of the shaft 50 56 may be varied to suit the different conditions. The zero point on the scale 3 will be the center point of the lap, as indicated in Figs. 7 and 8, and it is by locating the pivotal point of the frame 17 above or below 55 the zero point that I am enabled to provide for the grinding of the convex or concave lens, as will more fully hereinafter appear.

To support the swinging frame 15 when 60 the adjusting blocks 10 and 16 are being located to suit the different grinding operations, I provide the following mechanism.

A rock-shaft 61 is journaled in the base 65 of the pedestal 57 and a treadle 62 is connected to said rock-shaft. A spring 63 is connected with said treadle and with the

frame. Cams 64 are mounted on the shaft 61 and said cams engage the slides 65 moving in guides 66 in the base of the pedestal 57. The slides 65 are in line with the swinging frame 15 and when the treadle 62 is lowered these slides are brought up in position to temporarily support the frame 15 during the adjustment of the blocks 10 and 16.

In grinding a convex lens as indicated in Figs. 1 and 7, the said lens 54 is cemented 75 to the lens supporting block 41, and the frame 15 has been adjusted at the proper height to give the required curve to the lens, so that the lens will swing in an exact radius all the time of the grinding operation, the lens holder moving in an arc with the axis of the frame 15 as a center. The shaft 56 is elevated with the lap 55 bearing against the lens, and the machine is then put into operation. Suitable grinding material is delivered to the lap to give the necessary abrading action. Through the gears and connections described, power is applied to rotate the shafts 20 and 56 in opposite directions, and at the same time, 80 through the connections described, the frame 15 is oscillated to and fro. When once the desired curve to be given to the lens has been figured out and the frame adjusted according to the scale 3, no further attention 85 need be paid to the machine as the lens will swing in an exact radius at all times and there will be an equal wearing of all parts of the grinding surface of the lap. In this case the pivotal point of the swinging frame 17 is above the zero point on the scale, and consequently, I obtain the result indicated in Fig. 7, in which a convex lens is being ground. It is apparent that a flat topped lap might be employed for grinding a convex lens by my invention, although the operation would take longer than with a concave lap such as illustrated. The fact that the screw rods 4 adjust the blocks 10 simultaneously and move said blocks an equal 100 amount, makes it possible to effect the adjustment of the blocks 10 with reference to the scale with great accuracy, and the arc through which the frame 15 is to swing 105

can be readily varied by connecting the link 110 35 to the crank arm 36 at different points on said arm. The swinging frame 15 is very sensitive, being mounted as it is upon the knife edge trunnions. The spring 53 holds the lens in close contact with the lap to make 115 the abrasives grind the lens more rapidly. 120

In case it is desired to grind a prism or spheroprism, the lens supporting block 41 may be adjusted in the position indicated in Fig. 6, which will hold the lens in proper 125 position with reference to the lap for the grinding of a prism.

For the grinding of a concave lens the blocks 10 and 16 will be lowered on the scale to a point below the zero point of the 130

scale 3, and in that case the point of fulcrum of the swinging frame 15 is changed so as to provide for grinding of a concave lens, the proper form of lap being secured to the shaft 56. This is clearly indicated in Fig. 8, where the swinging point of the frame 17 is below the zero point on the scale, or below the center of the lap. The curve to be given to the lens can be very accurately calculated by the point at which the swinging frame is arranged with reference to the scale, and this point may be readily varied either for the grinding of a concave or convex lens.

While I have illustrated my invention with a single grinding device mounted in the frame 15, it is apparent that the frame 15 may be extended to carry a plurality of such grinding devices, so that at one time the different stages of grinding may be carried on in the same apparatus, the first grinding with the rough abrading material and the successive ones with finer materials until the last, where the rouge is employed for polishing. In this way by a single machine the successive grinding steps can be carried out, the lenses being transferred from one to the other support until finally completed. The great advantage of the machine is that when once adjusted no further attention need be paid as the grinding is carried on with great accuracy, and the lens moves from center of lap to circumference or from circumference to circumference, and the lap will be kept spherically correct because the lens swings in an exact radius at all times wearing equally all parts of the grinding surface of the lap. By the words "rigidly mounted rotary lens holder" employed in the claims, I mean a lens holder which is held in its position against movement, and it not having a universal joint action.

What I claim is:

1. In grinding apparatus, the combination with a suitable frame, of adjustable blocks on said frame having segmental recesses therein, a swinging frame, knife edge trunnions on said frame engaging said segmental recesses in said blocks, a rotary lap, and means for swinging said swinging frame.

2. In grinding apparatus, the combination with a suitable frame, of adjustable blocks carried thereby having segmental seats, a swinging frame, adjustable knife edge trunnions on said swinging frame engaging said seats, a rotary lens holder carried by said swinging frame, a rotary lap, and means for swinging said swinging frame.

3. In grinding apparatus, the combination of a suitable frame, simultaneously adjustable blocks on said frame, a swinging frame trunnioned on said blocks, a rotary lens supporting block, a rotary lap and means for swinging said frame.

4. In grinding apparatus, the combination with a suitable frame, of blocks on said frame, rotary screw-shafts, a swinging frame trunnioned on said blocks, a rotary lens supporting block, a rotary lap, and means for swinging said swinging frame.

5. In grinding apparatus, the combination with a suitable frame, of a swinging frame supported thereby, means for swinging said frame, a spring actuated shaft in said swinging frame, means for rotating said shaft, a lens supporting block carried by said shaft, and a rotary lap.

6. In grinding apparatus, the combination with a suitable frame, of a swinging frame mounted thereon, a vertically movable shaft in said swinging frame, means for rotating said shaft, a lens supporting block carried by said shaft, a spring actuated pin engaging the upper end of said shaft, a means for moving said pin out of engagement with said shaft, and a rotary lap.

7. In grinding apparatus, the combination with a suitable frame, of a swinging frame, mounted thereon, a vertically movable shaft carried by said swinging frame, means for rotating said shaft, means for swinging said swinging frame, a lens supporting block carried by said shaft, a spring actuated pin carried by said bracket engaging the upper end of said shaft, and a rotary lap.

8. In grinding apparatus, the combination with a suitable frame, of a swinging frame mounted thereon, a shaft on said frame, a lens supporting block carried by said shaft, a flexible longitudinally movable power-driven shaft, connections between said shaft and said first named shaft, a rotary lap, and means for swinging said swinging frame.

9. In grinding apparatus, the combination with a suitable frame, of a swinging frame mounted thereon, a shaft carried by said frame, a lens supporting block carried by said shaft, a flexible longitudinally movable shaft, connections between said shaft and said first named shaft, a rotary sleeve engaging said flexible shaft, means for rotating said sleeve, an extension on said swinging frame between said extension and crank-arm, connections between said crank-arm and said rotary sleeve, and a rotary lap.

10. In grinding apparatus, the combination with a suitable frame, of adjustable blocks on said frame, a swinging frame, adjustable blocks on said swinging frame, trunnions on said last named adjustable blocks engaging said first named adjustable blocks, a rotary lens supporting block carried by said swinging frame, a rotary lap, and means for supporting said swinging frame, while the adjusting blocks thereof are being adjusted.

11. In grinding apparatus, the combination of a suitable frame, of adjustable blocks carried thereby, a swinging frame, adjustable blocks on said swinging frame, trunnions on said last named blocks engaging said first named blocks, a rotary lens supporting block carried by said swinging frame, a rotary lap, and movable supports below said swinging frame.
12. In grinding apparatus, the combination of a suitable frame, adjustable blocks carried thereby, a swinging frame, adjustable blocks on said swinging frame, trunnions on said last named blocks adapted to engage said first named blocks, a rotary lens supporting block, a rotary lap, a rock shaft, cams on said rock shaft, and movable supports engaged by said cams and adapted to be moved in position to support said frame.

In testimony whereof, I the said WILLIAM E. HICE, have hereunto set my hand.

WILLIAM E. HICE.
